UNITED STATES PATENT OFFICE.

MAUNSELL B. JACKSON, OF TORONTO, ONTARIO, CANADA.

ENGINE STARTER.

Application filed July 27, 1925. Serial No. 46,343.

This invention relates to engine starters adapted to start internal combustion engines, and more particularly to that type in which a starter pinion is axially moved into and out of mesh with a gear on the engine. The pinion is normally out of mesh with the gear and when the starter is actuated the pinion is axially moved, due to inertia, into mesh with the gear. As soon as the engine is started the speed of the gear and thus the pinion is increased which causes the latter to be axially moved out of mesh with the gear. Heretofore it has been the general practice to provide an abutment for limiting the return movement of the pinion but the shock of the latter against the abutment is so great the pinion will rebound from the abutment and thus be fed again into engagement with the gear. The object of the present invention is to provide simple means to overcome this objectionable feature and to prevent any damage to the teeth of the pinion and gear if they meet end to end.

I attain my objects by means of the constructions hereinafter described and illustrated in the accompanying drawings in which

Fig. 1 is a side elevation of part of my starter shaft;

Fig. 2 a side elevation, partly in section, of my starter showing the pinion in its inoperative position;

Fig. 3 a side elevation showing the pinion in its operative position;

Fig. 4 an end elevation of Fig. 1;

Fig. 5 a cross section on the line 5—5 in Fig. 2;

Fig. 6 a cross section on the line 6—6 of Fig. 3;

Fig. 7 a longitudinal section of the pinion;

Fig. 8 an end view of the same;

Fig. 9 a longitudinal section of the nut;

Fig. 10 an end elevation of the same;

Fig. 11 an end view of the collar;

Fig. 12 a side and end view of a spring washer;

Fig. 13 a detail in cross section of the parts as shown in Fig. 5; and

Fig. 14 a similar view showing the parts in a different position.

1 is an extended armature shaft of an electric motor (not shown). The shaft is turned down at 1^a to form a shoulder 1^b against which a washer 1^c is positioned to form an abutment adapted to engage one end of a spring 2. This spring is disposed

on one end of a sleeve 3 which is slidably mounted on the portion 1^a of the shaft and the other end of the spring normally engages the ends of a double or triple thread 3^a formed on the sleeve. The latter is rotatably connected with the shaft by means of a clutch formed of a plurality of projections 3^b adapted to be received in recesses 4^a formed in a collar 4. The collar is slidably mounted on the shaft and is driven therewith by means of a key. A nut 5 threaded on the outer end of the shaft engages the collar to move it and thus the sleeve 3 axially on the shaft against the tension of the spring 2.

A pinion 6 loosely threaded on the sleeve is adapted to be axially moved into and out of mesh with a gear 7 connected with the crankshaft of an engine (not shown), the common practice being to secure this gear to the engine fly wheel. When the shaft 1 is set in motion the pinion is axially moved, due to its inertia, from its normal position, as shown in Fig. 2, into mesh with the gear. When the engine is started the speed of the gear is increased relative to the normal speed of the pinion whereby the pinion is rotated relative to its shaft and is thus axially moved out of mesh with the gear. The collar 4 is adapted to limit the outward movement of the pinion. To prevent the latter rebounding from the collar and re-meshing or contacting with the gear, I provide the pinion with means for frictionally engaging the sleeve threads.

One end of the pinion is counterbored at 6^a to receive a nut 8 threaded on the sleeve 3 and having a projection 8^a adapted to engage one end of a curved spring 9, the other end of which engages a projecting end 6^b of one of the pinion teeth. The end of the tooth 6^c which is adjacent the end 6^b is cut away to permit partial rotation of the projection 8^a.

The counterbore adjacent its outer end is recessed at 10 to receive the spring washer 10^a adapted to engage the nut 8 to limit its axial movement relative to the pinion 6. A housing 11 carried by the collar 4 is adapted to enclose the parts. The spring 9 tends to rotate the nut and pinion relative to one another (see Figs. 5 and 13), whereby the threads 8^b on the nut 8 engage the forward sides of the threads 3^a, and the threads 6^a on the pinion engage the rear sides of the threads 3^a to frictionally lock

the pinion in its inoperative position. As hereinbefore mentioned, the pinion is loosely threaded on the sleeve which permits a limited rotary movement of the pinion 5 threads relative to the sleeve threads without moving the pinion axially of the sleeve. When the shaft and thus the sleeve are rotated to start the engine, the threads 3^a and the threads 8^b are rotated relative to 10 the threads 6^a, due to the inertia of the pinion, which releases the frictional engagement of these parts and permits the pinion to be axially moved into mesh with the gear 7. As soon as the pinion starts to mesh with 15 the gear, the latter prevents the pinion rotating which results in the shaft being threaded through it. The pinion is adapted to engage the spring 2, see Fig. 3, which limits its axial movement and permits the shaft, sleeve 20 and nut to be further rotated relative to the pinion until the forward sides of the threads 3^a engage the threads 6^a to form a drive connection between the shaft and pinion and thus rotate the gear 7. When 25 the engine starts the pinion 6 is rotated relative to the shaft which axially moves it out of mesh with the gear, as hereinbefore described, and permits the spring 9 to again act on the pinion and nut to frictionally engage the threads 3^a.

Should the teeth of the pinion and gear meet end to end, the axial movement of the former towards the gear will be stopped which will permit the spring 9 to rotate the 35 pinion relative to the nut until the pinion threads 6^a engage the sleeve threads 3^a. As this is a very sudden engagement the pinion threads slide along the sleeve threads which causes the pinion to be axially moved away 40 from the gear. It is thus obvious that, with the above construction there will be no constant rubbing or grinding action between the gear and pinion which results in their teeth being damaged.

45 By adjusting the collar 4, as hereinbefore described, the amount of travel of the pinion into and out of mesh with the gear may be varied.

What I claim is:

50 1. In a starter for use with an internal combustion engine, the combination of a starter shaft provided with a thread; a pinion threaded on the shaft and having a limited rotary movement relative to the thread; a nut threaded on the shaft and freely carried by the pinion; and a spring tending to rotate the nut and pinion relative to one another to frictionally lock the pinion against movement towards the starting position, release being effected by a relative rotary movement of the shaft and pinion when the former is set in motion.

55 2. In a starter for use with an internal combustion engine, the combination of a starter shaft provided with a thread; a

pinion loosely threaded on the shaft; a nut threaded on the shaft and carried by the pinion; and a spring tending to rotate the nut and pinion relative to one another to frictionally engage the adjacent sides of their threads with the sides of the shaft thread, the pinion thread being disengaged from the shaft thread by a relative rotary movement of the nut and pinion when the shaft is set in motion.

75 3. In a starter for use with an internal combustion engine, the combination of a starter shaft provided with a thread; a pinion loosely threaded on the shaft, the pinion being counterbored at one end; a nut 80 threaded on the shaft adapted to be freely mounted in the said counterbore; and a spring tending to rotate the nut and pinion relative to one another to frictionally engage the adjacent sides of their threads with the sides of the shaft thread, the pinion thread being disengaged from the shaft thread by a relative rotary movement of the nut and pinion when the shaft is set in motion.

85 4. In a starter for use with an internal combustion engine, the combination of a starter shaft provided with a thread; a pinion loosely threaded on the shaft, the pinion being counterbored at one end; a nut threaded on the shaft adapted to be freely mounted in the said counterbore and provided with a projection; and a curved spring having one end in engagement with the pinion and the other end in engagement with the projection and tending to rotate the pinion relative to the nut, whereby the pinion and nut frictionally engage the opposite sides of the shaft thread, the shaft when set in motion being adapted to move relative to the pinion and thus disengage the thread of the latter from the thread of the former.

90 5. In a starter for use with an internal combustion engine the combination of a starter shaft; a sleeve mounted on the shaft and adapted to be driven thereby and provided with a thread; an abutment; a pinion threaded on the sleeve; a spring disposed on the sleeve and having one end in engagement with the abutment and the other end normally in engagement with the thread on the sleeve and adapted to engage the pinion; and means for limiting the outward movement of the pinion adapted to be adjusted on the shaft against the pressure of the said spring.

95 6. In a starter for use with an internal combustion engine the combination of a starter shaft having one end threaded; a collar keyed on the shaft; a sleeve mounted on the shaft and having a driving connection with the collar and provided with a thread; an abutment; a pinion loosely threaded on the sleeve, the collar being adapted to limit the outward movement of the pinion; a spring disposed on the shaft 100

normally engaging the abutment and the shaft thread and adapted to engage the pinion; and a nut threaded on the end of the shaft to adjust the collar axially of the shaft.

5 7. In a starter for use with an internal combustion engine having a gear for revolving the crank shaft thereof the combination of a starter shaft provided with a plurality of threads; a pinion loosely threaded on the 10 shaft and adapted to be axially moved into and out of mesh with the gear; a nut threaded on the shaft and carried by the pinion; a spring tending to rotate the nut and pinion relative to one another to cause the adjacent 15 sides of each of their threads to yieldingly engage the opposite sides of a shaft thread, the shaft when set in motion being adapted to move relative to the pinion to disengage the pinion thread from the shaft 20 thread; and an abutment adapted to engage the pinion to limit its axial movement when it is fully meshed with the gear, whereby the shaft is further rotated relative to the pinion to form a rotary drive connection be- 25 tween the shaft and pinion.

8. In a starter for use with an internal combustion engine having a gear for revolving the crank shaft thereof the combination of a starter shaft provided with a plurality of threads; a pinion loosely threaded on the 30 shaft and adapted to be axially moved into and out of mesh with the gear; a nut threaded on the shaft and carried by the pinion; and a spring tending to rotate the nut and pinion relative to one another to cause the 35 adjacent sides of each of their threads to yieldingly engage the opposite sides of a shaft thread, the shaft when set in motion being adapted to move relative to the pinion to disengage the pinion thread from the 40 shaft thread, the spring being adapted to rotate the pinion relative to the shaft thread to bring the pinion thread suddenly into engagement with the shaft thread and thus cause the pinion to slide along the shaft 45 thread and move axially away from the gear if the pinion does not mesh with the gear.

Signed at Toronto, Canada, this 20th day of July, 1925.
